UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

FUSE-CLIP.

1,092,430.

Specification of Letters Patent.

Patented Apr. 7, 1914.

Application filed March 17, 1913. Serial No. 754,921.

To all whom it may concern:

Be it known that I, ROBERT C. COLE, a citizen of the United States, residing at Hartford, in the county of Hartford and 5 State of Connecticut, have invented a new and useful Improvement in Fuse-Clips, of which the following is a specification.

This invention relates to the construction of those clips which are provided for receiving the terminals of inclosed fuses of the knife blade contact type, and particularly such fuses as are designed to carry relatively large currents, although of course these clips may be used for receiving the 15 terminals of fuses of small capacity.

Fuses, especially those of large capacity, require a proper area of contact between the surfaces of their terminals and the surfaces of the clips with which they are connected, and these clips are usually made in the form of spring fingers in order that the fuses may be quickly placed in or removed from the circuit. Such spring fingers must press tightly against the fuse terminals over 20 a considerable area otherwise the flow of current between the clips and the fuse terminals causes heating, which heating not only materially affects the carrying capacity of the fuse and its action when blown, but 25 also tends to soften and destroy the elasticity of the clip fingers. If the elasticity of the fingers is destroyed, they are liable to become more or less bent and stay bent when a fuse is inserted or removed, and this 30 increases the objectionable factor of improper contact and consequent heating.

The object of this invention is to construct a terminal clip which is particularly designed for large fuses, although it may 40 be used for small fuses, in such manner that the spring contact fingers which bear against the surfaces of the fuse terminals, cannot be spread so far apart as to impair their elasticity, and also to so construct a 45 clip that should the spring fingers not have any elasticity or should lose their elasticity as a result of heating, they will still be forced together by spring arms that will not become hot and will continue to make 50 such close contact with the fuse terminals as to eliminate the causes for overheating. To accomplish this end the usual spring clip contact fingers are provided for engaging the fuse terminals. Back of these spring 55 fingers are abutments which prevent the

80 fingers from being unduly spread and bent outward sufficiently far to affect the closeness of their contact with the fuse terminals. Outside of these stopping walls are 85 spring arms of stiffer and more highly tempered metal which bear against the outer surfaces of the spring clips and force them toward each other should the elasticity of the spring clips become impaired, the outer spring arms being so far away and having 90 contact against such small area of the spring fingers that they will never become overheated, for they do not carry current and on account of their location and amount of 95 exposed surface they will radiate heat faster 100 than they receive it.

Figure 1 of the accompanying drawings shows a plan of a fuse clip which embodies the invention. Fig. 2 shows a side view of the same. Fig. 3 shows a section on the 75 plane indicated by the dotted line 3-3 on Fig. 1.

The clip illustrated has a base 1 which is 80 desirably a brass casting. At one end on top this base has split contact lugs 2 which by screws 3 may be closed down upon the conducting terminal sleeve 4. Near the other end the base has upwardly projecting abutment walls 5 and between these walls are the spring fingers 6. These fingers may 85 be made of copper, bronze or similar material, and are designed to receive the terminal of the fuse and make contact sufficiently close and over a sufficiently large area to insure the proper flow of current 90 without undue heating. Outside of the abutments and extending upwardly and engaging the outer surfaces of the upper ends of the spring fingers are spring arms 7. These are desirably made of sheet steel so 95 tempered as to have considerable elasticity. Between the lower ends of the spring fingers is a spacing block 8. The parts are 100 tightly drawn together and secured by means of the bolt 9 and nut 10.

When the terminal of a fuse is thrust between the clip fingers they open outwardly and force back the spring arms. The normal elasticity of the spring fingers causes 105 them to grip the fuse terminal in the proper manner. These spring fingers are obstructed by the abutment walls back of them so that they cannot be spread by the careless insertion or removal of a fuse terminal sufficiently far to impair their elasticity and 110

render them incapable of proper contact with the fuse terminal. Should these spring fingers not have enough initial elasticity or should they lose their elasticity as a result of heating, they will still be forced together and caused to make proper contact with the fuse terminal by the steel spring arms back of them. The spring arms are so far away from the spring fingers and make contact with them over such a limited area, and not being obliged to carry current, do not become heated and lose their temper. With this construction, it is not even necessary to have the spring fingers which make contact with the fuse terminals and carry current so stiff and of such high temper as is required with the present form of clip, for the spring arms will close the fingers together with sufficient force to cause them to make the necessary contact to avoid heating.

The invention claimed is:

1. A fuse clip having a base, spring fingers on the base for receiving and making conducting contact with a fuse terminal, and an independent spring arm on the base bearing against the outer surface of each of the contact spring fingers and forcing said fingers toward each other.
2. A fuse clip having a base, spring fingers on the base and adapted to receive and make electrical contact with a fuse terminal, abutment walls on the base outside of said spring fingers to prevent them from being opened too widely, and an independent spring arm on the base and bearing against the outer surface of each of the contact fingers so as to force said contact fingers toward each other.
3. A fuse clip having a base, fingers supported by the base and adapted to receive and make electrical contact with a fuse terminal, abutments supported by the base ad-

jacent to the fingers and preventing them from being opened too widely, and spring arms supported by the base with their upper ends bearing against the outer surfaces of said fingers near the free ends thereof and forcing them toward each other.

4. A fuse clip having a base with terminal lugs and abutment walls, spring fingers arranged on the base between the abutment walls, and spring arms arranged on the base outside of the abutments and bearing against the outer surfaces of the spring fingers near the free ends thereof so as to force them toward each other.

5. A fuse clip having a base with abutment walls, fingers arranged between the walls, a spacing block between the fingers, spring arms bearing against the fingers and forcing them toward each other, and means for clamping the parts together.

6. A fuse clip having a base, resilient contact fingers attached to the base and normally closing toward each other, and resilient reinforcing arms attached to the base and bearing against the outer surfaces of the contact fingers, said arms and fingers having capacity to exert pressure and effect good electrical contact with a fuse terminal when inserted between the contact fingers.

7. A fuse clip having a base, a pair of fingers extending outwardly from the base for receiving between them and making electrical contact with a fuse terminal, and a pair of resilient arms extending outwardly from the base and having their free ends pressing against the outer surfaces of the contact fingers near the outer ends thereof.
